LIFTING-JACK.

1,395,821.

Specification of Letters Patent. Patented Nov. 1, 1921.

Application filed January 20, 1921. Serial No. 438,727.

To all whom it may concern:

Be it known that I, WILLIAM N. HARSEN, a citizen of the United States, residing at Attica, in the county of Lapeer and State of Michigan, have invented a new and useful Lifting-Jack, of which the following is a specification:

This invention relates to lifting jacks, and more particularly to double acting lifting jacks such as are adapted to effect a movement of the load both upon the up-stroke and down-stroke of the actuating lever. The invention may be considered as an improvement upon the construction disclosed in my co-pending application Serial Number 385768, filed June 1, 1920.

Said improvement consists in various structural features which are hereinafter fully described and are illustrated in the accompanying drawing, wherein:

Figure 1 is a view of the improved jack in side elevation, the two limiting positions between which the lever is rocked for raising the load being shown respectively in full lines and dash lines.

Fig. 2 is a similar view of the upper portion of the jack, showing the positions of the parts resulting from swinging the lever from the raised position shown in full lines in Fig. 1 to the lower limiting position.

Fig. 3 is a cross-section taken upon the line 3—3 of Fig. 1.

Fig. 4 is a similar view of the invention, showing in full lines the lower limiting position of the lever and corresponding positions of the parts when the load is being lowered, the other limiting position for lowering the load being indicated in dash lines.

Fig. 5 is a fragmentary side view of the jack showing the position of the parts corresponding to the raised position of the lever, when the load is being lowered.

Fig. 6 is a detail perspective view of a trigger, one of which is associated with each pawl to control engagement of the same with its rack.

In these views the reference character 1 designates the base of the standard or frame of the jack, 2 a pair of spaced parallel plates forming the sides of said standard, and 3 frame members interposed between the op-

posed vertical margins of the plates 2. Thus said standard has a rectangular tubular form, adapting it to house and guide a vertically actuatable plunger member formed by a pair of opposed spaced rack bars 4, integrally connected at top and bottom and integrally formed with a surmounted work table or platform 5. The teeth on each rack bar occupy an intermediate relation to the teeth of the opposed rack, the advantage of this arrangement being presently made clear. For actuating said plunger member vertically there is provided a lever comprising a pair of bars 6 extending respectively at opposite sides of the standard and pivoted upon a bolt 7 mounted in the upper portions of the plates 2 and passing between the two rack bars. In order to compound the leverage utilized in raising or lowering the load there is provided a secondary lever 8 which is pivoted at 9 between lugs 10 marginally formed upon the plates 2, and has a slot 11 in its outer end engaging a pin 12 connecting the bars 6 of the primary lever.

A handle member 13 is detachably engageable with the outer end of said secondary lever. Upon the bars 6 there are pivoted at 14 two pawls 15 and 16 of inverted U-shape, one at each side of the fulcrum bolt 7, the horizontal upper portions 17 of said pawls being engageable respectively with the two rack bars. Externally upon one of the plates 2 there is pivoted a pair of depending divergent trigger members 18, the pivot pin 19 for said members being positioned slightly above the fulcrum bolt 7 so that said members straddle said bolt. A leaf spring 20 is saddled upon the bolt 7 with its extremities bearing upon the ends of the two trigger members to maintain the desired divergence thereof. Adjacent their pivotal ends the pawls 15 and 16 have V-shaped cam projections 21 upon their opposed edges for engagement by said trigger members. Also the edges of said trigger members which engage said pawls have portions meeting at an obtuse angle to co-act with said cams. Intermediate their ends the pawls 15 and 16 are formed upon their opposed edges with rounded cam projections 22 which, under certain conditions presently to be explained, co-act with a

100

roller 23 journaled upon one of the plates 2 between the upper portions of said pawls.

Considering now the operation of the described invention, it is first to be understood that each swing of the handle 13, both upwardly and downwardly, is effected in shifting the load, the latter being raised when the movement of the handle is between the limits shown in Fig. 1, respectively in full lines and in dash lines, and being lowered when the angle of movement is between the wider limits, illustrated in Figs. 4 and 5. During actuation of the handle 13 from its upper limiting position shown in full lines in Fig. 1 to its lower limiting position, shown in dash lines in said figure, the plunger 4 and table 5 are raised from the position shown in Fig. 1 to that disclosed in Fig. 2. During this movement of the handle the pawl 16 is caused to rock on its pivots 14 due to the portion 17 of said pawl riding down the incline of one of the teeth of the engaged rack 4. Also during said movement of the handle the pawl 15 acts to raise the plunger 4 and the load thereupon. While the pawl 16 is being lowered the out-thrust exerted thereupon by the spring 20 acting through trigger 18^a maintains said pawl firmly pressed against the corresponding rack, so that after having ridden down the entire incline of the engaged tooth the pawl snaps into position below said tooth, as shown in Fig. 2. Similarly on the upstroke of the handle 13 the pawl 16 will raise the load and the pawl 15 will ride down a tooth of the corresponding rack and firmly engage therebeneath.

When it is desired to lower the load the handle 13 is first swung to one of its extreme positions, as for example that shown in Fig. 4. In this position the cam projection 21 of the pawl 16 engages the trigger member 18^a somewhat below the angle of the latter, so that the spring pressure is transmitted through said trigger member to the pawl at a considerable downward inclination. Under such conditions the pawl swings clear of the engaged rack 4 due to its own weight and rests, as shown in Fig. 4, against the roller 23. When the handle 13 is now raised to its other limiting position, shown in Fig. 5, said pawl clears the tooth of the rack 4 which it had engaged, and permits the other pawl, 15, to lower the load. After clearing the rack tooth which it had previously engaged, the pawl 16 is swung outwardly to engage the next higher tooth due to the cam projection 22 of said pawl encountering the roller 23. The continued upstroke of the handle 13, to bring the latter to its extreme upper position shown in Fig. 5, will effect a slight raising of the load through said pawl 16, but a considerably greater lowering of the load will occur during the subsequent down-stroke. On said down-stroke the load

will be carried by the pawl 16 while the pawl 15, due to its own weight, will incline clear of the associated rack, resting against the roller 23.

Thus it is seen that in the use of the described jack no manipulation or adjustment of the parts is necessary to change the operation from raising of the load to lowering thereof, or vice versa, this result being derived merely from a change in the angle through which the lever is swung.

Furthermore the construction is simple and its parts, being largely adapted to be formed as stampings from sheet material, may be produced at a relatively low cost.

What I claim is:

1. A lifting jack comprising a frame, a load carrying member vertically adjustable upon said frame, a pair of racks arranged in opposed spaced relation upon said load-carrying member, a lever pivoted upon said frame for actuating the load-carrying member vertically, pawls carried by said lever respectively engageable with said racks, a pair of divergent trigger members arranged between the pivotal ends of said pawls, and bearing thereupon, and a spring interposed between said trigger members and acting through the same upon the pawls to urge the same into engagement with their respective racks.

2. A lifting jack comprising a frame, a load-carrying member vertically adjustable upon said frame, a pair of racks arranged in opposed spaced relation upon said load-carrying member, a lever pivoted upon said frame for actuating the load-carrying member vertically, pawls carried by said lever respectively engageable with said racks, a pair of divergent trigger members arranged between the pivotal ends of said pawls, and bearing thereupon, and a spring interposed between said trigger member and acting through the same upon the pawls to urge the same into engagement with their respective racks, said pawls being respectively actuatable of their own weight clear of the racks in certain limiting positions of said lever, and being maintained by said spring in engagement with the racks when the lever is operated within narrower limits.

3. A lifting jack comprising a frame, a load-carrying member vertically adjustable upon said frame, a pair of racks arranged in opposed spaced relation upon said load-carrying member, a lever pivoted upon said frame for actuating the load-carrying member vertically, pawls carried by said lever respectively engageable with said racks, a pair of divergent trigger members arranged between the pivotal ends of said pawls, and bearing thereupon, a spring interposed between said trigger members and acting through the same upon the pawls to urge the same into engagement with their respec-

tive racks, said pawls having opposed cam projections and being actuatable of their own weight clear of the engaged racks in certain limiting positions of the lever, and being maintained by said spring in engagement with the racks when the lever is operated within narrower limits, and a projection

upon the frame of the jack engaged by the pawls when the latter are clear of the racks and acting upon said cam projections to 10 swing the pawls outward.

In testimony whereof I sign this specification.

WILLIAM N. HARSEN.
